UNITED STATES PATENT OFFICE.

JAMES F. McLAUGHLIN, OF PHILADELPHIA, PENNSYLVANIA.

TELEPHONIC APPLIANCE.

SPECIFICATION forming part of Letters Patent No. 328,702, dated October 20, 1885.

Application filed September 4, 1884. Serial No. 142,155. (No model.)

To all whom it may concern:

Be it known that I, JAMES F. McLAUGHLIN, a citizen of the United States, residing at Philadelphia, in the county of Philadelphia and State of Pennsylvania, have invented certain new and useful Improvements in Telephonic Appliances, of which the following is a specification, reference being had therein to the accompanying drawings, wherein—

10 Figure 1 is an elevation, partly sectional, of electric telephonic appliances embodying my invention. Figs. 2 and 3 are diagrams of same, illustrating the current or circuit connections, the former showing the bell in circuit with the line-wire and the telephone and transmitter cut out of same, and the latter showing the bell cut out of and the telephone and transmitter switched into the line-circuit; Figs. 4 and 5 are respectively an elevation 15 and plan of my improved telephonic or electric switch in position for placing the bell in the line-circuit and for cutting out of the same the telephone and transmitter; and Figs. 6 and 7 are like views of the switch in position 20 for cutting the bell out of and placing the telephone and transmitter in the line-circuit.

My invention has relation to electric telephonic appliances of that form which have a permanent magnet common to the telephone 25 and the call-bell, and has for its object simplicity of construction and the provision of a reciprocating or sliding switch for changing the circuits of the call-bell and telephonic appliances.

30 My invention accordingly consists of the combination, construction, and arrangement of parts, as hereinafter described and claimed.

In the drawings, A represents a box of any desired form and configuration, to which is 35 suitably secured, as desired, an electric call or bell, B, a magneto-electric machine, C, a transmitter, D, a telephone, E, and a switch, F.

The call-bell, magneto-electric machine, and the transmitter may be of any suitable or desired construction, and be disposed of or located as circumstances dictate.

One of the poles c of the field-magnets c' of the generator C is prolonged or provided with an extension, as shown at c^2 . This extension 40 c^2 may be an integral part of the pole or separate from and secured to it in any suitable manner. The pole-extension c^2 preferably

passes out through an opening in one of the sides a of box A, as shown, is provided with a helix, e , and surrounded by a casing, e' , having a diaphragm, e^2 , to provide an electric telephone, E, which is stationary or firmly secured to box A. To the casing or removable cover e^2 of the telephone is secured a depending flexible aural tube, G, having a mouth-piece, g .

Such construction provides, first, a magneto-electric machine, one of the poles of which serves as a core-piece or magnet for the helix e of the telephone, and, second, a combined magneto-electric generator and telephone having an aural tube for confining and directing the reproduced sounds to the ear.

From the foregoing it is evident that whenever a call is made or the armature c^3 of the generator C is rotated, the magnetism of the core-piece of the telephone is strengthened, or that the telephone is provided with means for duly and automatically maintaining its efficiency or always cause it to perform its functions in a clear and distinct manner.

If from continued disuse the telephone is weak or reproduces indistinctly, the subscriber can instantly and at any time increase its efficiency by a continued or prolonged rotation of the generator-armature c^3 .

A telephone so constructed is not subject to periodical repairing or replacing of worn-out magnets or core-pieces by new ones. Consequently, it is more durable, and the cost of maintenance of service is considerably reduced.

If desired, both poles c of field-magnets c' may be prolonged and duplicate telephones E mounted thereon and placed in suitable 90 electric circuit. Such prolongation of both poles of magnets c' is indicated in Fig. 1 by dotted lines x .

The switch F consists of a rod, f , sliding in a sleeve or tubular bracket, f' , and has at its 95 outer end two spring-arms, f^2 , and at or near its inner end a series of radial studs, f^3 , f^4 , and f^5 . The studs f^4 and f^5 are diametrically arranged, as shown. The stud f^3 is in line with a spring-finger, H, bent upon itself at h and having a turned-up end, h' . This finger H is in circuit with the electric bell or call B, by way of wire T. (See Figs. 2 and 3.) In contact with bar or rod f is a finger, I, having a

a ground-wire, 2, so that when finger H is in contact with studs f^3 the bell is in circuit with the line-wire y, or it is grounded by way of finger H, stud f^3 , bar f, and finger I, (see Figs. 2 and 4,) and the telephone and transmitter are cut out of the line-circuit.

The studs f^4 and f^5 are in line with a pair of spring-fingers, K and K', bent upon themselves at k and having turned-up end k'. When these fingers are in contact with the studs f^4 and f^5 , as shown in Figs. 3 and 7, the bell is cut out of the line-wire y and the telephone and transmitter are in circuit of same. To effect these changes of circuit, the bar f may be moved or reciprocated by hand, or such result may be effected by placing and withdrawing the aural tube G upon and from the switch-hook or spring-arms f^2 , and this operation is as follows: When the tube G is placed between the spring-arms f^2 of bar f, the act of pushing the tube into or between said arms slides the bar f in the direction of arrow 1. (See Figs. 4 and 5.) Such movement of bar f causes the stud f^3 to contact with fingers H, and the studs f^4 and f^5 to pass out of contact with fingers K and K', as shown, the finger I being always in contact with bar f, as shown. The bell is then switched into the line y and the telephone and transmitter cut out of same. When, however, the tube G is taken out of the switch-arms f^2 , the bar f is moved in a contrary direction, or in that indicated by arrow 2, Figs. 6 and 7, and such movement of bar f causes the stud f^3 to pass off the finger H and the studs f^4 and f^5 to contact with the fingers K and K', to cut out the bell and to switch the telephone and transmitter into the line-circuit y.

I do not wish to be understood as confining myself to the particular arrangement of circuits shown, as it is evident that they may be variously modified or changed, as desired, without departing from the spirit of my invention. So, too, it is also evident that instead of putting the studs f^3 , f^4 , and f^5 on the switch-bar f, they may be secured to the box A, in which case the fingers H and K K' will be attached to and move with the bar f.

What I claim is—

1. In a telephone appliance, the combination of call-bell, generator field-magnet C, having pole-piece extension c^2 , provided with a helix, e, a diaphragm, e^2 , mouth-piece E, having flexible tube G, and sliding switch F, arranged for operation, substantially as shown and described.

2. The combination, with call-bell B and telephone E, of a switch, F, comprising a sliding bar, f, studs f^3 , f^4 , and f^5 , and fingers H, K, K', and I, substantially as shown and described.

3. The combination, with a call-bell, B, telephone E, having aural tube G, and transmitter D, of a switch, F, comprising a sliding bar, f, with hook or spring arms f^2 , and contact-studs, and fingers, substantially as shown and described.

4. The switch F, comprising a sliding bar, f, having studs f^3 , f^4 , f^5 , and fingers H, K, K', and I, constructed and arranged to operate substantially as shown and described.

In testimony whereof I affix my signature in presence of two witnesses.

JAMES F. McLAUGHLIN.
